UNITED STATES PATENT OFFICE.

HARRY M. HART, OF PHILADELPHIA, PENNSYLVANIA.

DESIGN FOR A FOOT-SCRAPER.

41,843.

Specification for Design.

Patented Oct. 10, 1911.

Application filed April 4, 1911. Serial No. 618,941. Term of patent 7 years.

To all whom it may concern:

Be it known that I, HARRY M. HART, a citizen of the United States, residing at Philadelphia, in the county of Philadelphia and State of Pennsylvania, have invented a new, original, and ornamental Design for a Foot-Scraper, of which the following is a specification, reference being had to the accompanying drawing, forming part thereof.

The figure is an elevational view of a foot scraper, showing my new design.

The foot scraper is cut from a sheet of metal in the form of an animal, with the back shaped so as to serve as the functional part of the foot scraper.

I claim:

The ornamental design for a foot scraper substantially as shown and described.

HARRY M. HART.
